UNITED STATES PATENT OFFICE

2,525,813

DISTILLATE FUEL MANUFACTURE INVOLVING EXTRACTION WITH LIQUID HF

Nathan Fragen, Hammond, Ind., assignor to Standard Oil Company, Chicago, Ill., a corporation of Indiana

Application December 13, 1947, Serial No. 791,511

7 Claims. (Cl. 196—13)

1

This invention relates to distillate fuel manufacture and it pertains more specifically to the manufacture of high quality distillate fuels, such as heater oil, furnace oil and Diesel fuel from high sulfur crudes such, for example, as West Texas crude oil.

Heretofore distillate fuels have been produced as by-products in the manufacture of gasoline and such fuels of relatively high quality could be obtained from fractions of the virgin crude oil or from the cracking of virgin crude oil or from mixtures of virgin and cracked products. The phenomenal increase in demand for distillate fuels brought about by increased use of oil burners, replacement of steam locomotives by Diesel engines on railways, etc., coupled with the fact that high quality crude oils, such as Mid-Continent crude, are insufficient to meet demands and hence must be replaced by high sulfur crude oils has presented a serious problem to the oil refining industry. An object of this invention is to provide an improved method and means for obtaining the necessary amounts of high quality distillate without sacrificing yields or quality of gasoline and other products produced when high sulfur crude oil is employed as a charging stock.

An important characteristic of an acceptable distillate fuel is that it have a low sulfur content. Generally speaking, the sulfur content should not exceed about .5% and even a lower sulfur limit is desirable (although for some purposes a sulfur content as high as 1% may be tolerated). Distillate fuel fractions from Mid-Continent virgin gas oil contain only about .1 to .2% sulfur and even the cycle stock from the cracking of such gas oil has a sulfur content not substantially higher than about .2%. West Texas gas oil, however, is characterized by a sulfur content of the order of about 2% and the cycle stock from the cracking of such gas oil has sulfur contents upwards of 1%, e. g. approximately 1.5% or more. An object of the invention is to provide distillate fuels from high sulfur crudes without interfering with maximum gasoline production, said distillate fuels having a sulfur content not substantially higher than about .5%.

Another desired characteristic of a distillate fuel is its freedom from tendencies toward coke and soot deposits. Extensive tests have shown that a virgin or cracked distillate fuel can be rated in this respect by a burning quality index which will be hereinafter referred to as BQI and which will be hereinafter defined or characterized

2

by setting forth the precise test for its determination. The BQI of a distillate fuel is an index of its quality for its intended use which is comparable to "octane number" as a quality index for gasoline. For satisfactory burning qualities, i. e. sufficient freedom from coke formation and soot depositing tendencies, a distillate fuel should have a BQI of at least about 60. Thus a distillate fuel fraction of an M-C virgin gas oil having an API gravity of 34.6, a 10% distillation point of 49° F., a 50% point at 564° F. and a 90% point at 619° F. has a BQI of about 80. The cycle stock produced by cracking such gas oil and characterized by a gravity of 36.0° API, a 10% point of 368° F., a 50% point of 414° F. and a 90% point of 470° F. has a BQI of about 71. However, a distillate fuel produced by the cracking or coking of West Texas gas oil may have a BQI of only about 20, the BQI of some fractions being as low as —10. An object of the invention is to provide distillate fuels from high sulfur crudes without interfering with maximum gasoline production, said distillate fuels having a BQI of at least about 60.

25 Distillate fuels usually boil in the range of about 350 to 750° F., the so-called heater oils (for pot type and sleeve type burners) boiling chiefly in the range of 350 to about 550° F. or more (some having end points as high as up to about 700° F.) and Diesel fuels boiling chiefly in the range of about 400 to 650° F. or more. It is desirable to manufacture furnace oils of sufficiently low sulfur content and high cetane number that they can also be utilized as Diesel fuels. For such use the cetane number of the fuel should be at least about 40 and preferably about 50 or more. Mid-Continent light virgin gas oil Diesel fuels are characterized by a cetane number upwards of 50 and the cycle stock produced by the cracking of gas oils have a cetane number upwards of 40. However, Diesel fuel fractions produced by cracking or coking of high sulfur crudes, such as crudes from West Texas, have a cetane number of only about 35 although it varies with conversion. An object of the invention is to provide distillate fuels from high sulfur crudes without interfering with maximum gasoline production, said distillate fuels having a cetane number of at least about 40 and preferably about 50 or more.

50 An important object of the invention is to accomplish each of the above objects simultaneously and at the same time to produce, in addition to maximum yields of gasoline, a marketable

coke and a valuable by-product extract which may find important utilization in the agricultural and construction industries.

In practicing the invention a high sulfur crude oil or a charging stock consisting essentially of high sulfur crude oil, may be processed primarily for production of maximum gasoline yields by the catalytic cracking of the gas oil fraction and the coking of the residual fraction under conditions which are now well known in the art. The gas oils produced in such operations are then extracted with HF at a temperature in the range of about 50 to 150° F. and with an amount of HF in the range of about .05 to 2 volumes, preferably about .5 volume, per volume of gas oil charged. The extraction is preferably effected in a countercurrent system designed to provide intimate contact and adequate time of contact which may be in the range of about 10 to 60 minutes, e. g. about 30 minutes but which will depend somewhat upon the intimacy of contact. Particularly in the case of coke still gas oil, which may constitute one of the largest refinery streams and which constitutes the most difficult problem, the contacting and/or separation of HF and gas oil may be effected in the presence of a small amount of a light paraffinic hydrocarbon such as normal hexane or a pentane or similar cut of light naphtha; such hydrocarbon is not primarily for the purpose of reducing viscosity but it has been found to minimize emulsion difficulties and to facilitate phase separation as well as to facilitate solvent removal after the extraction step. Yields of gas oil raffinate obtainable in such extraction processes range from about 75% to 90% and the extract obtained has unique properties which may make it useful for impregnating compositions for the protection of wood and other fibrous materials against the action of termites, marine borers, etc.

The extraction effects a surprising improvement in the characteristics of the oil which are of such importance in the distillate fuel field without substantially changing the distillation temperature of the various boiling range fractions, particularly those fractions which are desired in the distillate fuel field. The resulting fuel oil fractions are thus characterized by sulfur content not substantially exceeding about .5%, usually in the range of about .1 to about .3%, a BQI of upwards of about 60 and a cetane number upwards of about 40 or 50. In addition to these important improvements the fuel oil fractions are further improved by having a lower bromine number, density, refractive index and specific dispersion. The improved BQI means that it has a remarkably lower tendency to deposit carbon on burning.

The invention will be more clearly understood from the following detailed description read in conjunction with the accompanying drawing which forms a part of this specification and which schematically illustrates a flow diagram of the improved process.

Referring to the drawing, a high sulfur crude oil or a crude oil mixture consisting chiefly of high sulfur crude from source 10 is fractionated in a conventional manner schematically represented by crude fractionator 11 into a residual fraction which is withdrawn through line 12 to coker 13, a virgin gas oil fraction which may be withdrawn through line 14 to catalytic cracking system 15 and a lighter-than-gas-oil fraction which is withdrawn through line 16 and subjected to known processes for the production of

high quality motor fuel. The virgin gas oil fraction may, if desired, be withdrawn with the residual fraction as a part of the reduced crude.

The coking of the reduced crude or residual fraction is essential for obtaining maximum gasoline and distillate fuel oils from the crude oil. No novelty is claimed in the coking operation per se since it is well known to those skilled in the art and it will not be described in great detail. Briefly, the process comprises the subjecting of the reduced crude to temperatures of the order of about 850 to about 1000° F., e. g. 900° F., at a pressure of about atmospheric to 100 p. s. i., usually about 50 p. s. i., for sufficient time of contact to convert the charge into solid coke, coke still gas oil and coke still naphtha with some formation of lighter hydrocarbons. The coke is removed at 17 and marketed as such. The coke still naphtha is removed at line 18 and may be catalytically reformed for effecting desulfurization and octane number improvement by conventional methods. The coke still gas oil, however, has presented the most difficult problem for petroleum refiners because it is not particularly desirable as a charging stock for thermal and catalytic cracking and because it possesses none of the essential characteristics required for meeting distillate fuel specifications.

The coke still gas oil is withdrawn through line 19 and if it contains any moisture it should be dried by passage through drying towers or other conventional drying equipment. From line 19 the coke still gas oil is introduced into HF extraction tower 20 (which may be packed with 1-inch carbon rings 21 supported on grid support 22) where it is intimately and countercurrently contacted with liquid HF introduced through line 23. The extraction may be effected in a batch or multiple batch system or in a continuous tower type reactor or in any other known manner. It has been found however that best results are obtained when a small amount, for example about 2 to 20% or approximately 10%, of a light hydrocarbon or mixture of hydrocarbons of the butane to heptane boiling range, for example hexane, is introduced either by line 24 below the coke still gas oil inlet or by line 25 with the gas oil charge, the former giving the best results.

The amount of solvent may be varied within the fairly wide range of about .05 volume to 2 volumes or more of HF per volume of coke still gas oil charged but from a quality yield standpoint it has been found that good results are obtained with from about .2 to about .5 volume of HF per volume of gas oil charged. Thus using approximately .3 volume of HF per volume of gas oil charged, a raffinate yield of about 81.5% has been obtained with a sulfur content of .43. The extraction may be effected at ordinary atmospheric temperature or within the range of about 50 to 150° F. and the time of contact may be about 10 to 60 minutes, e. g. about 30 minutes, although shorter times may be employed if greater intimacy of contact is obtained.

The extract from the countercurrent extraction system is withdrawn through line 26 to extract stripper 27, which may be provided with suitable top cooling or reflux means such for example as introduction of condensed HF at the upper part thereof. The extract stripper is provided with conventional heating means 28 which may be supplemented by the use of an inert stripping gas such as propane, butane, etc. The stripping gas and removed HF are withdrawn through line 29 and the extract material through line

30. The final extract may be contacted with bauxite for decomposing any alkyl fluorides in accordance with conventional practice in the HF alkylation art. This material has unique properties which may prove to be of importance in wood impregnating compounds and the manufacture of resins and plasticizers. Such extract may contain 5 or 6% by weight of sulfur and it may be characterized by an A. P. I. gravity of about 6 to 8 with a boiling range higher than that of the 10 charging stock. The extract itself may be subjected to a coking operation and when coked at about 1000° F. yields about 63% liquid product, 13% coke, and 24% gas, the total liquid product containing about 6% and the coke about 3% of sulfur.

The raffinate from the extraction system 20 is withdrawn through line 31 to raffinate stripper 32 which is provided with conventional reboiler or heating means 33 and also with suitable top cooling or reflux means. A cooler and acid settler may be interposed in 31 for the separation and direct recycling of any HF that may be separated from the raffinate by such procedure and an inert stripping gas such as propane, butane or the like may supplement heat as a means for removing the HF from the raffinate material. The HF and stripping gas leave stripper 32 through line 34 and may be combined with materials from line 29, the combined materials being cooled in cooler 35 and introduced into settler 36. The separated HF may be withdrawn from the settler through line 37, supplemented when necessary by makeup HF from line 38 for introduction through line 23 to extraction system 20. The upper hydrocarbon layer may be withdrawn from settler 36 through line 39 and at least a part of it may be withdrawn through line 40 or returned to low points in the stripping towers. At least a part of the hydrocarbons may be passed by lines 41 and 24 to a low point in the extraction tower 23 in place of or in addition to makeup hexane or light paraffinic hydrocarbon introduced through line 42.

The gas which may contain H₂S, vented from the top of settler 36 through line 40a and/or the stream from line 40 may be processed in any known manner for recovering residual HF therefrom. For example, the gas stream from line 40a may be scrubbed with a lean oil under conditions for dissolving HF, the undissolved material may be vented from the top of the scrubber, the rich oil from the base of the scrubber may be heated to release the dissolved HF, the liberated HF may be returned to the system, and the denuded lean oil may be cooled and returned to the top of the scrubber (not shown). The stripped raffinate passes from the base of stripper 32 through line 43 to fuel oil fractionator 44 which is diagrammatically illustrated as a simple tower but which may consist of any conventional or known fractionation system provided with conventional reboiling and reflux means. Any remaining dissolved HF may be removed from the stripped raffinate by passing it through line 45 to scrubber 46 into which a caustic solution is introduced by line 47 and withdrawn through line 48. Conditions will be employed in fractionator 44 for obtaining distillate fuel of the described boiling range which, in the case of heater oil, may be about 350 to 500° F., in the case of furnace oil may be about 350 to 550° F. or more and in the case of Diesel

fuel may be in the range of about 400 to 650° F. or more. Distillate fuels of such boiling ranges may be withdrawn through line 49. The lighter fractions withdrawn through line 50 may be employed as a component of kerosene or naphtha and the heavier fractions may either be withdrawn for special use through line 51 or returned by line 52 to the catalytic cracking unit 15. The extraction step makes these heavy ends particularly suitable as a charging stock for the catalytic cracking step. At least a part of the distillate fuel boiling range fraction may also be introduced through lines 53 and 52 to catalytic cracking unit 15.

15 As a specific example, a West Texas crude was fractionated to give a 55% reduced crude characterized by an API gravity of 19.3, a sulfur content of 2.3% and a boiling range upwards of about 500° F. The reduced crude was subjected to a coking which operation resulted in wet gas yield of 6.3 wt. percent, a coke yield of 13.3%, a gasoline yield of about 10 volume percent and a coke still gas oil yield of about 75 volume percent, the latter having an API gravity of about 27.5, a wt. percent sulfur of about 1.8 and a boiling range of about 400° to about 750° F. Representative inspections on coke still gas oil as charged to an HF extraction unit and on a total raffinate therefrom as charged to a fractionator are as follows:

	Coke Still gas oil	Raffinate
35		
Volume Per Cent on Original	100.0	81.5
API Gravity	27.1	32.3
Weight Per Cent Sulfur	1.64	0.5
BQI	48	77
Bromine Number	24	5
Specific Dispersion	147	129
Refractive Index	1.4983	1.4814
Cetane Number	45	51
ASTM Distillation:		
Initial Boiling Point	370	258
10	490	482
30	566	566
50	625	629
70	684	691
90	746	748
Maximum	750	
Weight Per Cent Fluorine		0.005
Per Cent S in heater oil boiling range		Less than .05%

50 From the above inspections it will be noted that the total raffinate is characterized by a sulfur content of only .5, a BQI of 77 and a cetane number of 51. It will also be noted that the bromine number, specific dispersion and refractive index are markedly lower than on the coke still gas oil and the API gravity is materially higher although the distillation temperature of the 10% to 90% fractions is not materially changed.

60 Heretofore it was believed that HF would react with the olefins of such charging stocks to form alkyl fluorides; the extremely small amount of alkyl fluoride formation was surprising and although the raffinate may sometimes contain as much as .02% fluorine, a caustic wash is usually all that is required. Stripped extract may be contacted with bauxite for decomposing any residual alkyl fluorides and stripped raffinate may simply be scrubbed with a solution of sodium hydroxide or the like.

75 Since most distillate fuels are of narrower boiling range than the total raffinate it is important to know the properties of the components of different boiling range in the total raffi-

7
nate. Inspections on seven fractions of a representative raffinate are as follows:

Cut	Total Raffinate	1	2	3	4	5	6	7	Bottoms
Volume per cent on total Raffinate	0.476	5.0	5.0	5.1	5.0	5.2	5.2	5.2	61.2
Weight per cent S	0.039	0.039	0.039	0.058	0.084	0.122	0.172	0.217	0.690
°API	32.5	59.2	42.0	39.5	37.9	36.4	35.6	34.7	28.6
BQI	78.5	100+	96.6	89.0	85.0	82.4	81.2	79.2	-----
IBP	183	140	370	434	460	482	498	514	-----
10	493	160	404	456	481	504	524	536	-----
50	634	220	428	474	502	526	546	560	-----
90			412	454	496	528	554	576	586
Max	726	486	520	548	580	582	598	614	-----
ΔBQI	32	12.9	23.3	27.1	28.2	29.2	30.5	-----	-----

The above information shows that the low boiling fractions are remarkably low in sulfur content containing only about .04%. The last line of the above tabulation shows the increase in BQI over that of the corresponding fractions in the unextracted coke still gas oil.

The remarkable results accomplished by HF extraction of coke still gas oil are not obtained by processes heretofore known to the art. When 25 distillate fuel fractions of coke still gas oil are treated with sulfuric acid, desulfurization is disappointingly low even at treating with as much as 15 pounds of 98% sulfuric acid per barrel (which is about ten times the amount of acid currently used for stabilizing furnace oils). The unique character of coke still gas oil is shown by the fact that HF extracts from virgin gas oils and even from cycle gas oils produced by thermal or catalytic cracking can be almost completely (99% or more) desulfurized by hydrogenation over cobalt molybdate catalyst at 750° F. and 300 p. s. i. g. pressure with a space velocity of about .5 and with 24,000 cubic feet per barrel of added hydrogen; only about 80% of the sulfur could thus be removed from HF extract from coke still gas oil. Apparently the coking process changes the nature of at least a part of the sulfur compounds in a high sulfur charge and creates a sulfur removal problem which is not encountered with virgin or cycle gas oils. It appears that the sulfur compounds in the 500° or 600 to 700° F. boiling range are most difficult to remove by hydrogenation (hydrodesulfurization) and the invention is particularly applicable to such coke still gas oil fractions.

My HF extraction is surprisingly more effective on coke still gas oil than on virgin gas oil, as shown by the following comparative data on extractions with 30 weight percent HF;

	Virgin Gas Oil			Coke Still Gas Oil		
	Feed	Raff.	Extr.	Feed	Raff.	Extr.
°API	27.2	30.3	9.8	27.1	32.4	6.1
ASTM 50% °F	625	-----	-----	625	-----	-----
Weight Per Cent S	1.71	0.70	7.5	1.64	0.48	5.8
Volume Per Cent Yields	87.6	12.4	-----	81.5	18.5	65
Weight Per Cent Desulfurization	59	-----	-----	71	-----	-----

The sulfur and aromatics in coke still gas oil appear to be more soluble in HF than the corresponding compounds in virgin gas oil of similar boiling point. There appears to be a loss of selectivity when the amount of solvent is less than 10% or more than about 60 to 80% because of 70

8
the solution of more non-sulfur compounds into the extract phase.

A striking example of the unpredictable results obtainable by the invention is shown by a comparison of BQI improvement obtainable by extraction of M-C virgin heavy gas oil as compared with BQI improvement obtainable with coke still gas oil. Extraction of M-C heavy virgin gas oil with 28% HF solvent gave the following results:

	Volume Per Cent Yield	Per Cent Sulfur	°API	A. S. T. M.			BQI
				10	50	90	
30	Feed	0.45	30.3	574	656	748	73
	Raffinate	0.24	31.2	584	658	742	72
	Extract	5.7	1.7	-----	-----	-----	-----

35 Extraction of coke still gas oil chiefly of West Texas origin with 33 volume percent HF gave the following results:

	Volume Per Cent Yield	Per Cent Sulfur	°API	A. S. T. M.			BQI
				10	50	90	
40	Feed	100.0	1.64	27.1	490	625	746
	Raffinate	81.5	0.48	32.6	482	631	748
	Extract	18.5	5.80	6.1	-----	-----	48
45	-----	-----	-----	-----	-----	-----	84

50 The raffinate of the M-C gas oil showed an actual decrease in BQI by the extraction step while in the case of high sulfur coke still gas oil the BQI was increased from 48 to 84, the coke still raffinate BQI being materially higher than that of virgin M-C oils.

Now with regard to the significance of the BQI, it is well known that the various refinery stocks in the distillate fuel boiling range are by no means of the same quality. Some highly refined stocks give trouble-free performance in the most critical type burners while others are wholly unsatisfactory giving large deposits in relatively short periods of time. The need for a test method to rate the performance of a furnace oil in a burner is not unlike the earlier need of the industry for a device to measure the performance of gasolines in internal combustion engines. In this latter case the conventional octane scale has proven of great utility. With this thought in mind successful efforts were made to set up a somewhat similar scale for rating the performance of distillate fuels in burners. The "test burner" selected was a Coleman Model 821B Space Heater. This burner was chosen because it is typical of the most sensitive class of burners used commercially. The standard burner test involves determining the weight of the total

burner deposits when 10 gallons of fuel are burned at the rate of 0.3 gallon per hour employing 0.06 inch of water draft. The theoretically perfect fuel would, of course, give no burner deposits; such a fuel is arbitrarily defined as having a BQI of 100. The most highly refined selected refinery stocks, however, merely approach this ideal giving burner deposits of approximately 8 grams; such distillate fuels on this scale have a BQI of 100 minus 8 or 92. One of the poorer refinery stocks gives deposits as high as 90 grams; such a fuel has a BQI of 100 minus 90 or only 10. Thus, BQI is a measure of distillate fuel performance and may be defined as 100 minus the number of grams of burner deposits accumulated when 10 gallons of fuel are burned in the "test burner" at the rate and under the conditions mentioned above. The development of a process or method which converts stocks which are now unsatisfactory, i. e. with a BQI well below 60 to a product of the same boiling range with a BQI of 60 or higher represents a contribution of the utmost importance. In addition to the remarkable improvement in sulfur content and the phenomenal improvement in BQI, the invention accomplishes a like improvement in cetane number. Properties of coke still raffinate fractions in the heater oil and furnace oil boiling range were found to be as follows:

	Vol. Per Cent of Raff.	Per Cent Sulfur	°API	BQI	A. S. T. M.			Cet. No.
					10	50	90	
Heater Oil-Furnace----	15	0.06	39.9	89	439	471	515	53
	28	0.16	39.0	86	424	495	598	54

In addition to the above it should be noted that the distillate fuels produced by this invention have such good odor and such low copper numbers (about 2 or 3) that additional sweetening may be entirely unnecessary.

The data hereinabove set forth illustrate the remarkable and unpredictable results obtainable by HF extraction of coke still gas oil from high sulfur crudes. If the virgin gas oil from the high sulfur crude is charged to a catalytic cracking unit instead of a coking unit, the cycle oil produced in the catalytic cracking operation may be extracted with HF to give results which are advantageous but which are by no means the equivalent of the extraction of coke still gas oil. For example, a cycle gas oil from the catalytic cracking of a charge containing a large portion of West Texas origin was extracted with 47 volume percent HF with following results:

	Vol. Per Cent	Per Cent Sulfur	API	BQI	A. S. T. M.			Cet. No.
					10	50	90	
Feed-----		1.35	25.7	-10	476	534	667	65
Raffinate-----	79.1	0.33	32.7	59.4	464	525	640	
Extract-----	20.5	4.67	1.5	-----	496	639	-----	

It will be noted that the BQI of the raffinate was improved to a remarkable extent but not to the quality obtainable by extracting coke still oil. When the cycle oil was divided into a light catalytic cycle oil fraction and a heavy catalytic cycle oil fraction, these two fractions were separately extracted with HF using about 50% HF by volume

on the light fraction and about 40% HF by volume on the heavier fraction and the following results were obtained:

Stock	Vol. Per Cent Yield	Wt. Per Cent Sulfur	API	BQI	Cet. No.	A. S. T. M.		
						10	50	90
10 Feed-----		1.07	29.3	16	35	455	492	540
Raffinate-----	84.3	0.10	33.3	59.2	42	461	495	545
Extract-----	15.0	5.70	6.4	-----	-----	-----	-----	-----

Stock	Vol. Per Cent Yield	Per Cent Sulfur	API	BQI	A. S. T. M.			Cet. No.
					10	50	90	
15 Feed-----		1.79	21.8	-3	583	636	676	676
Raffinate-----	78.9	0.90	29.0	62	581	634	680	
Extract-----	21.6	4.52	0	-----	-----	-----	-----	

The light fraction did not result in as high a BQI as obtained with coke still gas oil and the heavier fraction shows much less desulfurization than obtainable with coke still gas oil.

The coke still gas oil itself may be catalytically cracked and the cycle oil thus produced may be extracted with HF. When coke still gas oil was thus catalytically cracked under conventional conditions the conversion was 42% and the properties of the cycle oil before and after HF extraction were found to be as follows:

Stock	Vol. Per Cent	Per Cent Sulfur	API	BQI	A. S. T. M.			Cet. No.
					10	50	90	
40 Feed-----		1.64	24.8	-10	489	562	692	692
Raffinate-----	76.6	0.43	31.6	60	474	552	675	
Extract-----	22.6	4.46	0	-----	-----	-----	-----	

When the coke still gas oil was first extracted with HF and only the raffinate subjected to catalytic cracking the conversion was considerably higher, 55%, and the properties of the cycle gas oil before and after extraction were as follows:

Stock	Vol. Per Cent	Per Cent Sulfur	API	BQI	A. S. T. M.			Cet. No.
					10	50	90	
55 Feed-----		0.71	28.9	28	486	540	660	660
Raffinate-----	87.1	0.31	32.7	62	481	535	639	
Extract-----	12.3	3.1	0	-----	-----	-----	-----	

The catalytic cracking may be effected in fixed bed, moving bed or powdered catalyst systems all of which are well known to the art and which require no detailed description. The so-called fluid catalytic cracking process is preferred, such for example, as that illustrated on page 63 of the Petroleum Engineer, January, 1945, and described by Murphree et al. in Oil and Gas Journal of March 3, 1945, at page 64 et seq. The catalyst may be an acid treated montmorillonite clay or of the synthetic silica alumina or silica magnesia type having a small particle size. The catalyst to oil ratios may be in the range of 2:1 to 20:1 on a weight basis, the cracking temperature may be in the range of about 800 to 1000° F., e. g. about 900° F. at a gauge pressure of the order

of 5 to 15 pounds per square inch and with a weight space velocity in the range of .2 to 20 pounds of oil charged per hour per pound of catalyst in the reactor. The charging stock passes upwardly through the reactor at a velocity in the range of about 1 to 3 feet per second and sufficiently low to maintain the catalyst in dense phase turbulent suspension, a portion of the catalyst being continuously withdrawn to a separate regenerator from which regenerated catalyst is constantly returned to the reactor. Since no invention is claimed in the catalytic cracking step per se, no further description of it is necessary.

Gasoline is withdrawn from the catalytic cracking system through line 54 and lighter-than-gasoline products through line 55. The heavier-than-gasoline components, usually referred to as catalytic cycle oil, are withdrawn through line 56 and at least a portion thereof may be withdrawn from the system through line 57 for separate utilization. Such catalytic cycle oil may however be markedly improved by passing it through lines 58 and 19 to the HF extraction system 20 and extracting it with HF under substantially the same conditions as hereinabove described in the case of coke still gas oil. Here again the optimum HF to oil ratio for the extraction step appears to be in the general vicinity of .5 volume of HF per volume of oil undergoing extraction. Under such conditions the raffinate yield is about 80 to 85% and representative inspections of the total cycle gas oil, raffinate and extract respectively are as hereinabove tabulated.

As hereinabove pointed out, at least a portion of the HF extracted coke still gas oil may be charged to the catalytic cracking step. It has been found that when unextracted coke still gas oil (from West Texas crude) is charged to the catalytic cracking step employing an activated clay or natural cracking catalyst, the activity of the catalyst decreases quite rapidly, the amount of conversion correspondingly decreases and the weight percent of coke based on charge rapidly increases. However, when such coke still gas oil is extracted with HF to give about 81.5% raffinate as hereinabove described and the extracted gas oil is charged to catalytic cracking, the initial conversion is considerably greater. The effect of the extraction step on catalyst deterioration in the cracking step is shown by the following tabulated results of an experimental program:

Feed Stock	Feed, Weight Per Cent S	Hours on Stream	Per Cent Conversion	Carbo-naceous Deposit, Weight Per Cent	Catalyst Activity
Coke Still Gas Oil	1.66	11	50.0	6.2	21.4
HF Extracted Coke Still Gas Oil	1.66	60	43.4	9.2	14.9
Coke Still Gas Oil	0.50	10	57.6	5.0	23.2
	0.50	106	55.3	4.2	22.3

"Catalyst activity" as herein employed means the number of parts by weight of a fresh reference catalyst that would be required to obtain the same extent of conversion as is effected by 100 parts by weight of the catalyst being rated under the same operating conditions. ("Determination of Activity and Selectivity of Cracking Catalyst" presented by Shankland and Schmitkons at November 10, 1947, meeting of American Petroleum Institute.) The decline of catalyst activity with coke still gas oil enormously decreases the conversion which can be effected in a given catalytic cracking unit, and said decline in activity can be substantially avoided by proper HF extraction of the charge.

The product distribution in the catalytic cracking step is likewise remarkably improved by the

HF extraction step as shown by the following results:

5	Feed Stock	Carbo-naceous Deposits, Weight Per Cent	Gasoline Yield, Volume Per Cent	Gasoline, CFR-M			Light Cycle Oil	
				Clear	1 cc.	3 cc.	BQI	Per Cent S
10	Coke Still Gas Oil	5.3	37	70.7	81.8	83.5	0	1.3
	HF Extracted Coke Still Gas Oil	2.4	43	78.3	82.0	85.2	55	0.6

15 Although the light cycle oil from the catalytic cracking of HF extracted gas oil is of somewhat lower quality for distillate fuel oil preparation than extracted coke still gas oil itself, certain fractions thereof will meet BQI and sulfur specifications and the BQI improvement in particular is remarkable. It should be noted that the HF extraction lowers the coke yield to less than half of its original value, markedly increases the gasoline yield and produces a gasoline which, with the addition of tetraethyl lead in amounts of 1 cc. and 3 cc. respectively, is even superior to the gasoline produced from unextracted coke still gas oil.

20 It should be emphasized that the HF extraction in all cases is effected without the necessity of employing BF_3 or other additives which so greatly increase the cost and difficulty of refining.

25 While preferred examples of the invention have been described in considerable detail it should be understood that the invention is not limited thereto since numerous alternative procedures and operating conditions will be apparent from the above description to those skilled in the art.

I claim:

30 1. A method of obtaining a high quality distillate fuel, which method comprises coking a virgin high boiling fraction of a high sulfur crude oil, effecting said coking at a temperature between about 850° F. and about 1000° F. at a pressure between about 15 and about 100 p. s. i. to produce principally a coke still gas oil having an A. P. I. gravity below 30, more than 1 weight percent of sulfur and a burning quality index less than 50, extracting said coke still gas oil with liquid hydrogen fluoride in an amount between about 20 and about 50 percent by volume, based on said coke still gas oil, at a temperature between about 50° F. and about 150° F. to produce a raffinate, fractionally distilling said raffinate to obtain a distillate fuel oil fraction boiling between about 350° F. and about 650° F., the last-named fraction having a sulfur content not in excess of about 0.3 weight percent and a burning quality index of at least 75.

35 2. The method of producing high quality distillate fuel from a coke still gas oil obtained by the coking of a high boiling fraction of a high sulfur crude oil at a temperature in the range of about 850° F. to about 1000° F. at a pressure between about 15 and about 100 pounds per square inch to produce principally a coke still gas oil having more than one weight per cent of sulfur and a burning quality index not higher than about 50, which method comprises contacting said coke still gas oil with liquid hydrogen fluoride at a temperature in the range of about 50° F. to 150° F. with a hydrogen fluoride to oil volume ratio which is greater than .1:1 and less than .6:1 with a time of contact less than 60 minutes but sufficient to produce a raffinate having a sulfur con-

tent not substantially in excess of about 0.5 weight per cent, separately removing hydrogen fluoride from the raffinate and extract produced in the contacting step, and fractionating the hydrogen fluoride-free raffinate to obtain a distillate fuel oil fraction boiling chiefly in the range of 350° F. to 650° F., said distillate fuel oil fraction having a sulfur content not in excess of about 0.3 weight per cent and a burning quality index of at least about 75.

3. The method of producing high quality distillate fuel from a coke still gas oil produced by coking a high boiling fraction of a high sulfur crude oil at a temperature in the range of about 850° F. to about 1000° F. and a pressure in the range of about 15 to 100 pounds per square inch to produce principally a coke still gas oil containing more than one weight per cent of sulfur and having a burning quality index not higher than about 50, which method comprises extracting said coke still gas oil with liquid hydrogen fluoride in an amount between about 20 and about 50 per cent by volume, based on said coke still gas oil, at a temperature between about 50° F. and 150° F., employing in the extraction step a contact time which is less than 60 minutes and sufficient with the intimacy of contact employed to produce a yield in the range of 75% to 90% of a raffinate which when freed from hydrogen fluoride is characterized by a sulfur content not higher than about .5 weight per cent and a burning quality index of at least about 60, and separately removing hydrogen fluoride from the raffinate and extract produced in the extraction step.

4. The method of producing, from a high sulfur crude petroleum, a hydrocarbon oil boiling chiefly in the range of 350° F. to 700° F. and having a sulfur content less than about 0.5 weight per cent and a burning quality index of at least about 60, which method comprises coking a high boiling fraction of said high sulfur crude oil at a temperature in the range of about 850° F. to 1000° F. under a pressure in the range of about atmospheric to 100 pounds per square inch for a time of contact sufficient to effect production of coke still gas oil, components lower boiling than gas oil and coke, said coke still gas oil having a sul-

fur content higher than one weight per cent and a burning quality index not substantially higher than about 50, extracting said coke still gas oil with liquid hydrogen fluoride at a temperature in the range of about 50° F. to 150° F., at a pressure sufficient to maintain liquid phase extraction conditions with an amount of liquid hydrogen fluoride between about 20 and about 50 per cent by volume based on said coke still gas oil and with a contact time in the extraction step of less than 60 minutes but sufficient with the intimacy of contact employed to produce a yield in the range of 75% to 90% of a raffinate having a sulfur content not substantially in excess of about 0.5 weight per cent and a burning quality index of at least about 60, and separately removing hydrogen fluoride from extract and raffinate produced in the extraction step.

5. The method of claim 4 which includes the further step of diluting the coke still gas oil in the extraction step with about 2 to 20 per cent of a light hydrocarbon of the butane to heptane boiling range.

6. The method of claim 4 which includes the further step of coking the extract after removal of hydrogen fluoride therefrom.

7. The method of claim 4 which includes the further step of catalytically cracking the raffinate after removal of hydrogen fluoride therefrom by contacting said raffinate with a solid cracking catalyst of the class consisting of acid treated clay, synthetic silica alumina and silica magnesia at a temperature in the range of about 800° F. to about 1000° F.
